UNITED STATES PATENT OFFICE.

HARRY A. CUMFER, OF CHICAGO, ILLINOIS, AND ALBERT D. STEWART, OF DAYTON, OHIO.

PLASTER-RECEIVING BOARD.

Application filed June 21, 1921. Serial No. 479,181.

To all whom it may concern:

Be it known that we, HARRY A. CUMFER and ALBERT D. STEWART, citizens of the United States, respectively residing at Chicago, in the county of Cook and State of Illinois, and at Dayton, in the county of Montgomery and State of Ohio, have invented certain new and useful Improvements in Plaster-Receiving Boards, of which 10 the following is a specification.

The invention relates to improvements in plaster receiving boards.

One of the objects of the invention is to provide an improved plaster receiving board 15 or sheeting to which to apply and key plaster.

Another object is to provide an improved means to key the plaster to such supports.

Another object is to provide a plaster receiving board that is waterproof, easy to apply, inexpensive to manufacture, sufficiently strong and remarkably durable.

Other, further and more specific objects of the invention will become readily apparent, to persons skilled in the art, from a consideration of the following description, when taken in conjunction with the drawings, wherein:—

Fig. 1 shows a section taken on line 1—1 30 of Fig. 2.

Fig. 2 is an elevation of a wall showing part after the plaster has been applied.

Fig. 3 is a section on line 3 of Fig. 2 of 35 one form of the device showing the manner in which the plaster keys through the openings in the sheet.

Fig. 4 is a similar view taken on line 4 of Fig. 2 showing another form of opening.

Fig. 5 is a face view of a portion of a 40 sheet showing the sort of opening shown in Fig. 4.

In all the views the same reference characters are employed to indicate similar parts.

The plaster receiving sheet may be made 45 of strawboard, coated on each side with a more or less adhesive waterproof material, such as asphalt. At suitable intervals, openings are punched through the plasterboard 50 to provide keys to receive the plaster, to thus mechanically hold the plaster in intimate contact with the supporting structure.

The board may be made of a plurality of 55 sheets stuck together; two or three as the situation may require, and both sides of each

sheet, in any event, are covered with the wind resisting waterproof coating, or the waterproofing material may be incorporated with the fibrous material in the beater engine. The invention includes any manner 60 of making the board waterproof.

Instead of punching parts out to provide the holes 5 parallel slits 6 and 7, connected together by the mid-portions and separated by a slit 8, are preferably made through the 65 board to provide wings 9 and 10 which open laterally by application of pressure at the time when the plaster 11 is applied to the wall.

The outward deflection of the wings 9 and 10 to admit the plaster keys 12 serve, in each instance, as an arch and strengthen the board to hold the plaster in place. The board appears at the rear, after the plaster is applied, as a series of closely proximating laterally extending arches. The result is that they contribute very largely to the strength of the board, and when the board is part of a ceiling the plaster is thus prevented from sagging. The stress, due to the weight of 80 the plaster, is resisted at the keys by the wings in line with their length and not transversely thereof, the key of the plaster operating just as the keystone of an arch in its effect upon the supporting members thereof. 85

The board may be made in continuous sheets and rolled up into rolls for convenient shipping and storing, just as asphalt roofing is made and prepared for the market.

The drawings show a three-ply board 13 90 nailed to studs 14 by nails 15. The board may be made of any suitable width, 32 inches or 48 inches wide, to conveniently bridge two or more spaced apart studs.

By coating the fiber board on both of its 95 sides with a water-proof material it will not buckle appreciably upon application of the moisture contained in the green plaster and the fibrous material is thereafter protected from the deleterious effect of moisture due 100 to changing atmospheric conditions.

Having described our invention what we 105 claim as new and desire to secure by Letters Patent is:—

1. A plaster receiving board having a plurality of uniformly spaced apart unobstructed openings, each opening bounded on two of its opposite sides by wings arranged to be laterally deflected from the board, thereby to form an arcuate plaster support on the 110

side of the board opposite to that on which the plaster is applied, said wings provided by two parallel slots and a transverse slot connecting the median portions of the parallel slots, between which the wings are formed.

2. A plaster receiving board comprising a plurality of suitable, united sheets, having a series of spaced apart unobstructed openings therein when the plaster has been ap-

plied, each opening bounded on its sides by two flexible outstanding wings, with their free edges facing and extending away from the side to which the plaster is to be applied.

In testimony whereof we hereunto set our hands.

HARRY A. CUMFER.
ALBERT D. STEWART.
